G. R. CHASE

URINAL

Filed Oct. 30, 1922

Inventor

G. R. Chase

By *Watson E. Coleman*
Attorney

UNITED STATES PATENT OFFICE.

GEORGE R. CHASE, OF JEFFERSON, OREGON.

URINAL.

Application filed October 30, 1922. Serial No. 597,900.

To all whom it may concern:

Be it known that GEORGE R. CHASE, a citizen of the United States, residing at Jefferson, in the county of Marion and State 5 of Oregon, has invented certain new and useful Improvements in Urinals, of which the following is a specification, reference being had to the accompanying drawings.

This invention relates to certain improvements in urinals and it is an object of the invention to provide a novel and improved device of this general character especially designed and adapted for use by invalids and people temporarily or permanently confined to their beds and also for the use of people who may be suffering from bladder trouble or other ailment which would require them to rise frequently and particularly where lavatories or the like are not 20 convenient.

It is also an object of the invention to provide a novel and improved device of this general character which may be readily employed by a person of either sex and which 25 may be used with convenience lying on the side or on the back.

Another object of the invention is to provide a novel and improved device of this general character constructed in a manner 30 whereby the same may be properly handled by the person and without the necessity of a nurse or other assistance.

The invention consists in the details of construction and in the combination and arrangement of the several parts of my improved urinal whereby certain important advantages are attained and the device rendered simpler, less expensive and otherwise more convenient and advantageous for 40 use, as will be hereinafter more fully set forth.

The novel features of my invention will hereinafter be definitely claimed.

In order that my invention may be the 45 better understood, I will now proceed to describe the same with reference to the accompanying drawings, wherein:

Figure 1 is a view in perspective of a urinal constructed in accordance with an embodiment of my invention;

Figure 2 is an enlarged fragmentary sectional view taken through the upper portion of the device as illustrated in Figure 1; and

Figure 3 is a transverse sectional view taken through the structure as disclosed in 55 Figure 2.

As disclosed in the accompanying drawings, 1 denotes an elongated member of desired dimensions and which has produced therein a relatively large opening 2 elliptical in form and with the major diameter of said opening disposed lengthwise of the member 1. One end portion of the member 1 is continued to provide an elongated handle or operating member 3, herein disclosed as coplanar with the member 1, of a width materially less than the width of the member 1. C denotes a container the walls of which being preferably made of rubber sheeting. The container C is provided with a neck 5 which is 70 insertable through the opening 2 in the member 1, the walls of said neck being returned to surround the adjacent portions of the member 1, said return portions a being suitably secured to the neck 5 below the member 75 1. The operation of the device is believed to be apparent without a detail explanation being given.

From the foregoing description it is thought to be obvious that a urinal constructed in accordance with my invention is particularly well adapted for use by reason of the convenience and facility with which it may be assembled and operated, and it will also be obvious that my invention is 80 susceptible of some change and modification without departing from the principles and spirit thereof and for this reason I do not wish to be understood as limiting myself to the precise arrangement and formation of 85 the several parts herein shown in carrying out my invention in practice except as hereinafter claimed.

I claim:

1. A urinal comprising an elongated member provided with an extension at one end to provide an operating handle, said member being also provided with an elongated opening, the major axis of the opening being disposed lengthwise of the member, and a con- 100

tainer supported by the member and having an induction opening in communication with the opening of the member.

2. A urinal comprising an elongated member provided with an extension at one end to provide an operating handle, said member being also provided with an elongated opening, the major axis of the opening being dis-

posed lengthwise of the member, a container provided with a neck, the walls of said neck being insertable through the opening of the member and engaged with the adjacent portions of the member. 10

In testimony whereof I hereunto affix my signature.

GEORGE R. CHASE.
